UNITED STATES PATENT OFFICE.

MARTIN B. SCHENCK, DECEASED, LATE OF MERIDEN, CONNECTICUT, BY WILLIAM A. SCHENCK, EXECUTOR, OF MERIDEN, CONNECTICUT, ASSIGNOR TO THE M. B. SCHENCK COMPANY, OF MERIDEN, CONNECTICUT, A CORPORATION OF CONNECTICUT.

CASTER.

1,022,800.

Specification of Letters Patent.

Patented Apr. 9, 1912.

Application filed January 27, 1912. Serial No. 673,828.

To all whom it may concern:

Be it known that MARTIN B. SCHENCK, deceased, late a citizen of the United States, residing at Meriden, in the county of New Haven, State of Connecticut, did invent a new and useful Improvement in Casters, of which the following is a specification.

This invention relates to improvements in casters for metal beds and the like, and has for its object to produce a caster which will be securely held within a hollow leg by spring pressure, being centered therein so as to relieve the holding spring from undue pressure due to lateral stress, said casters supporting the hollow leg and being provided with a spring frame whose upper end embraces the pintle, and whose arms engage the upper end of the centering frame so as to reinforce the spring action at the bottom of the spring frame, the expansive and compressive movement of the spring being thus limited.

The following is a description of my invention, reference being had to the accompanying drawings, in which—

Figure 1 shows a plan view of the caster. Fig. 2 shows a side elevation of the same, with the hollow leg indicated in dotted lines. Fig. 3 shows a section on the line 3—3, Fig. 2.

Referring more particularly to the drawings, 1 is a hollow leg shown in dots.

2 is a supporting plate or disk upon which the leg 1 rests. 3 is a caster pintle carrying the yoke 4, in which is mounted the caster wheel 5 in the ordinary manner. Said disk 2, when the caster is in use, rests upon the boss 6 so as to be supported thereby.

7 is a centering frame preferably made of sheet metal in the form of an inverted U and having tongues 8 passing through slots 9 in the disk 2 and bent over so as to secure the frame 7 to the disk. The frame 7 is provided with a perforation in its upper end, through which the pintle 3 passes, and the pintle is swaged so as to form a flange 10 near its upper end, which holds the pintle to the frame 7. The frame 7 is provided with openings in the center of its ends adjacent to the disk 2, through which a spring frame 11 closed at its lower end passes, as shown in Figs. 2 and 3. This spring frame has a bend 12, which partially encircles the pintle 3 adjacent to the disk 2 and is provided with two upright bulging arms, which at their upper ends are provided with loops 13—14, which encircle the upper end of the pintle 3 above the frame 7. These loops are somewhat elongated, so as to loosely embrace the pintle and permit the upper ends of the arms of the spring 11 to have a movement of expansion and compression. In Fig. 1, they are shown in full lines in compressed position. In Fig. 2, they are shown in full lines in expanded position, and in dotted lines in compressed position. The upper ends of the arms of the spring 11 are preferably made so as to embrace the pintle 3 loosely and above the upper end of the frame 7. The lower ends of the bulging arms are connected by the portion 12, so that the spring frame has a permanently closed lower end adjacent to the supporting disk 2. The upper end of the frame 7 is slightly indented at 15—15, so as to assist in retaining the spring 11 in position, and permit the bends at the upper end of the spring to be made less abrupt. With this construction the caster is inserted and removed as with the various types of metal bed casters heretofore in use, that is, the caster is forced into the hollow leg, the spring 11 being compressed by such action, and when the caster is in place the spring 11 holds it in position by frictionally engaging the inner surfaces of the tubular leg, the leg itself resting upon the supporting disk 2. The caster is centered by the engagement of the four corners of the centering frame 7 with the inner sides of the leg so as to relieve the spring from undue pressure. In this way the centering is secured entirely independent of the retaining spring 11, thereby producing a caster which is strong and efficient and not liable to be injured in use. The upper ends of the spring 11 bear against the pintle, as shown in Fig. 1, when the caster is in use, thus reinforcing the spring action at the lower end of the spring frame, the forcing of the caster into the leg tending to straighten the bowed arms of the spring. This spring action in some instances is also reinforced by the engagement of the arms with the bottom of the recesses 15 at the top of the centering frame.

The invention, as will be evident to those skilled in the art, permits of modifications

which will embody the spirit thereof without departing from the scope of the claims annexed hereto.

What I claim as the invention of said

5 MARTIN B. SCHENCK is:

1. In a caster, the combination of a 10 caster wheel, yoke and pintle with a supporting disk surrounding said pintle, a centering frame secured to said disk and adapted to engage the inner surface of a tubular leg, said pintle having its upper end passing through said frame and engaged thereby, and a spring frame having its lower end adjacent to said disk and its upper end embracing said pintle.

2. In a caster, the combination of a 20 caster wheel, yoke and pintle with a supporting disk surrounding said pintle, a centering frame secured to said disk, said pintle having its upper end passing through said frame and engaged thereby, and a spring frame having a closed end adjacent to said disk and its upper end embracing said pintle above the top of said centering frame.

25 3. In a caster, the combination of a caster wheel, yoke and pintle with a supporting disk surrounding said pintle, a centering frame secured to said disk, said pintle having its upper end passing through said frame and engaged thereby, and a spring frame having a closed end adjacent to said disk and two independently movable arms embracing said pintle above the top of said centering frame.

30 4. In a caster, the combination of a caster

wheel, yoke and pintle with a supporting disk surrounding said pintle, an inverted U-shaped centering frame secured to said disk, said pintle having its upper end passing through said frame and engaged thereby, and a spring frame having a closed end adjacent to said disk and two independently movable arms loosely embracing said pintle said spring frame extending through notches located in the lower ends of the arms 45 of said centering frame and adjacent to said disk.

5. In a caster, the combination of a 50 caster wheel, yoke and pintle with a supporting disk surrounding said pintle, an inverted U-shaped centering frame secured to said disk, said pintle having its upper end passing through said frame and engaged thereby, and a spring frame having a closed end adjacent to said disk and two independently 55 movable arms embracing said pintle above said centering frame, said spring frame extending through notches located in the lower ends of the arms of said centering frame and adjacent to said disk and having its lower end partially surrounding said pintle, said centering frame having notches at its upper end which receive the upper ends of the arms of said spring frame.

WILLIAM A. SCHENCK,
Executor of the will of Martin B. Schenck.
